UNITED STATES PATENT OFFICE

FRANK ANTICH, OF ST. LOUIS, MISSOURI

LIFE-SAVING BOAT

Application filed July 9, 1928. Serial No. 291,435.

This invention relates to life saving devices and its general object is to provide an enclosed water-tight life saving boat that is primarily designed for submarine vessels and the like and is adapted to be detachably secured to the deck of a vessel with water-tight means of communication between the same and the interior of the vessel, whereby the occupants of the vessel may pass therefrom into the life saving boat which when released from the vessel, if the latter is submerged will rise to the surface, with the result the boat is extremely useful in saving the occupants of disabled submerged vessels in an easy and expeditious manner.

Another object of the invention is to provide a life saving boat for submarine vessels and the like, that is adapted to be detachably secured to the vessel and includes means for supporting the boat when secured, and said means also serves as a keel or center board when the boat is floating so as to prevent undue rolling thereof.

A further object of the invention is to provide a life saving boat of the character set forth, that is capable of housing supplies and drinking water, and can be steered whereby it can be directed as desired after being released from the vessel carrying the same.

A still further object of the invention is to provide a life saving boat for submarine vessels, that is shaped to overcome resistance to a minimum so as not to retard the speed of a submarine when the latter is submerged, and the boat will not materially interfere with efficient operation of the submarine vessel when attached thereto.

Another object of the invention is to provide a life saving boat that is rather simple in construction, inexpensive to manufacture and install, and is efficient in operation and service.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying draw-

ings wherein like characters denote like or corresponding parts throughout the several views, and in which:

Figure 1 is a view illustrating the application of my life saving boat to a submarine vessel and the manner in which the boat rises to the surface when detached from the submarine vessel.

Figure 2 is a sectional view taken approximately on line 2—2 of Figure 1 looking in the direction of the arrows.

Figure 3 is a longitudinal sectional view taken through the life saving boat per se.

Figure 4 is a fragmentary bottom plan view.

Figure 5 is a similar top plan view.

Referring to the drawings in detail, it will be noted that while I have illustrated my life saving boat as being associated with a submarine vessel, I want it understood that it can be used with any marine vessel, but is extremely useful in saving the occupants of a disabled submerged submarine.

The submarine vessel as shown is of any well known type and for distinction is indicated by the letter A. The submarine vessel has arranged on its deck at appropriate places openings in the nature of manholes and secured to the deck and rising from about the openings are flanged members 1 having upstanding annular flanges as best shown in Figure 2 of the drawings.

The life saving boat is provided with an annular flange 2 depending centrally of its bottom and being of a size to snugly fit within the annular flanges of the flange members 1, and the life saving boats are adapted to be secured to the deck of a vessel through the instrumentality of bolt and nut connections 3 extending through the bottom of the boat about the annular flanges 2 thereof and threadedly received in inwardly extending projections formed with the vessel and having threaded bores to accommodate the bolts as shown in Figure 2.

Formed in the bottom of the life saving boat is an opening adapted to be aligned with the openings formed in the vessel when the boat is secured thereto and the opening of the boat is closed by a hatch door 4 which is held

in operative position by latches 5 as best shown in Figure 4 of the drawings. The door 4 is provided with a suitable gasket so that a water-proof connection is formed between the door and its opening. By this construction, it will be apparent that the occupants of the vessel may pass therefrom into the life saving boat, when the vessel is submerged. Of course, the door 4 will be removed as long as the life saving boat is attached to the vessel, but when the occupants of the vessel have passed into the life saving boat, the door is replaced and secured in position by the latches 5.

The life saving boat includes a central compartment which as shown is cylindrical in formation and provides the quarters for the occupants thereof. The central compartment is indicated by the reference numeral 6 and disposed upon opposite sides of the opening formed in the bottom thereof are platforms 7 providing a floor. Arranged in the said compartment 6 are drinking water tanks 8 which have supported thereon food containers or boxes 9. A pump 10 may also be provided within the central compartment, as well as a radio set or like signalling means 11, and formed in the top of the life saving boat, preferably centrally thereof is an opening providing a manhole, and this opening is square, with a flange 12 rising from about the upper edges thereof as best shown in Figure 5 of the drawings.

The flange 12 supports a hatch door 13 which is secured in closed position by bolt and nut connections 14 arranged in a manner whereby the nuts can be removed from the bolts from the interior of the compartment 6.

The boat is further provided with portholes 15 arranged at the most appropriate places and these portholes may be of any well known construction but in any event are water-tight when closed.

The boat is formed with air chambers 16 extending from the opposite ends of the central compartments 6 and these air chambers are conical in form as best shown in Figure 3. Each of the chambers are provided with valved openings formed in the partitions 17 which provide the central compartment and these valve openings are designed for filling the chambers with air or removing some of the air therefrom if desired.

A rudder 18 is provided for the boat and includes a shank 19 extending into one of the air chambers 16. The shank 19 is mounted for rotation in a bearing 20 and has secured to its upper end a gear segment 21 which is disposed in mesh with a gear 22 secured to one end of a shaft 23 having secured to its opposite end a hand wheel 24 disposed within the central compartment as shown.

While the life saving boat may be made in various sizes in the event it is made in a relative large size, I provide a ladder 25 extend-

ing from one of the platforms to the hatch way or opening formed in the top of the compartment 6, so as to provide a convenient means of leaving the boat as will be apparent.

From the above description and disclosure of the drawings, it will be obvious that I have provided a life saving boat that can be detachably secured to vessels of all types and can be readily removed therefrom when desired. When it is necessary or desired to use a life saving boat, persons can freely pass therein through the medium of the opening formed in the bottom thereof, and when the required number of persons are in the life boat the latch door 4 is secured into place, then the boat is released from its vessel by removing the bolts of the bolt and nut connections 3 from their threaded bores. Should the vessel carrying the life saving boat be submerged, when the boat is released therefrom, it will rise to the surface due to the buoyancy supplied by the air in the air chambers 16, with the result that the boat can readily save the lives of the occupants of a disabled submerged vessel in an easy and expeditious manner.

Due to the novel shape of the life saving boat, it will set up very little resistance when secured to a submarine vessel and therefore will not materially retard the speed of the submarine vessel or the efficient operation thereof when the latter is submerged.

Depending from the bottom of the boat are spaced parallel longitudinally disposed strips 26 having inclined flanges 27 formed therewith for the purpose of securing the strips to the boat, and these strips not only act as appropriate supporting means for the boat when the latter is secured to a vessel as shown in Figure 2, but serve as keels to prevent undue rolling of the boat when the latter is floating.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:

A life saving boat comprising a cylindrical compartment, air chambers formed with the ends thereof, partitions dividing the compartments from the chambers and arranged at the juncture of the compartments with said chambers, said partitions having valved openings, means for closing inlet and outlet manholes formed in the top and bottom of said compartment and in alignment with each other, means for securing said boat to a vessel and being operable from the interior of said compartment, steering means for said

boat, longitudinally disposed strips depending centrally and vertically from said bottom upon opposite sides of the inlet man-hole, and flanges formed with the upper edges of said strips and being secured to the bottom.

In testimony whereof I affix my signature.

FRANK ANTICH.
